UNITED STATES PATENT OFFICE

146,645

DESIGN FOR A VEHICLE

Joseph E. Donalson, Kansas City, Mo.

Application April 15, 1946, Serial No. 128,599

Term of patent 7 years

(Cl. D34—15)

To all whom it may concern:

Be it known that I, Joseph E. Donalson, a citizen of the United States, residing at Kansas City, in the county of Jackson and State of Missouri, have invented a new, original, and ornamental Design for a Vehicle, of which the following is a specification, reference being had to the accompanying drawing, forming a part thereof.

Figure 1 is a perspective view of the vehicle, showing my new design; and

Fig. 2 is a rear elevational view thereof.

I claim:

The ornamental design for a vehicle, as shown.
JOSEPH E. DONALSON.
